CLAIM

The ornamental design for a spherical surgical container, as shown and described.

DESCRIPTION

FIG. 1 is a perspective view of a spherical surgical suction container showing our design;

FIG. 2 is an exploded top perspective view;

FIG. 3 is a bottom perspective view;

FIG. 4 is a left elevation view;

FIG. 5 is a right elevation view;

FIG. 6 is a front side elevation view;

FIG. 7 is a back side elevation view;

FIG. 8 is a top plan view; and,

FIG. 9 is a bottom plan view.

The dot-dash broken line showing of four circular features on the top side of the centrally located raised portions of the suction container shown in FIGS. 1, 2 and 8 are for the purpose of illustrating openings and forms no part of the claimed design.
